UNITED STATES PATENT OFFICE.

GEORGE P. MCENTIRE AND RALPH N. MCENTIRE, OF TOPEKA, KANSAS.

PORCH-SWING.

No. 909,317.

Specification of Letters Patent.

Patented Jan. 12, 1909.

Application filed August 3, 1908. Serial No. 446,564.

To all whom it may concern:

Be it known that we, GEORGE P. MCENTIRE and RALPH N. MCENTIRE, citizens of the United States, residing in Topeka, in the 5 county of Shawnee and State of Kansas, have invented a new and useful Improvement in Porch-Swings, of which the following is a specification.

The object of our invention is to provide a 10 strong, durable, and comfortable porch swing, one that is fully capable of withstanding the uses and abuses to which such an article is subjected.

Our invention is a porch swing made entirely 15 of metal, excepting some few details, comprising angle-iron frames and wire fabric, and attached co-operatively as will be hereinafter fully explained.

In the drawings accompanying and forming 20 part of this specification, and in the description of the drawings, we have shown our invention in its preferred form, and have shown the best mode of applying the principles thereof; but it is to be understood that 25 our invention is not confined to the exact details of construction shown in those drawings and in that description, and that we contemplate changes in form, proportions, materials, and arrangement, the transposition 30 of parts, and the substitution of equivalent members, within the scope of the appended claims, without departing from the spirit of the invention.

Figure 1 is a front elevation of a porch 35 swing made in accordance with the principles of our invention. Fig. 2 is a side elevation, a secondary position of the back and foot-rest being shown in dotted outline. Fig. 3 is an enlarged sectional view taken approxi- 40 mately on the line 3 of Fig. 1. Fig. 4 is an enlarged section taken on the line 4 of Fig. 3. Fig. 5 is an enlarged section taken on the line 5 of Fig. 3.

Similar reference characters indicate like 45 or corresponding parts throughout the several views.

The seat may have its frame made of angle-iron ends 6, 6, and angle-iron front and back strips, 7, 7, properly secured together 50 at the corners; while the main body of the seat may be made of a wire fabric 8, preferably of the kind shown, which consists of the wire links 9, disposed at right-angles, and connected with metal rings 10, the ends being 55 connected to the end strips 6, 6 of the frame by the extension springs 11. 12, 12 are

the front corner-posts, also made of angle-iron, and 13, 13 are the back posts; on which are supported the top end rails 14, 14, respectively; and these rails are preferably 60 merely extensions of the front corner posts bent at right-angles, and pivoted or bolted to the back posts. The posts may be properly braced by the brace rods 15, 15.

16 is a foot-rest pivoted at 17, 17 to the 65 front of the seat, and comprising an angle-iron frame and a wire fabric similar to the frame and fabric of the seat, as indicated in the drawings. 18 is the back, also comprising an angle-iron frame and a wire fabric 70 similar to the seat, and pivoted to the rear of the seat at 19, 19.

Secured under each end rail 14 is a rack 20, adapted to be engaged by a loop 21 formed in the end of a rod 22 which is pivoted 75 to the back 18 at 23. Also pivoted to the back 18, at each end of the seat, is another rod 25, pivoted at 24, the other end being pivoted to a lever 26 which is pivoted to the end strip 6 at 27, the other end of the lever 80 being pivoted to a link 28 which connects it with the foot-rest 16.

29 is an arm rest placed upon each of the top rails 14 and secured thereto by an eye-bolt 30 at each end. A chain 31 is secured 85 to each eye-bolt for sustaining the swing.

A cushion 32 may be provided for the back; and a cushion 33 may be provided for the seat, with a drop 34 for the foot-rest.

By lifting the loop 21 with the hands, and 90 pressing against the back, the back may be tilted rearwardly to any desired position, where it may be held by dropping the loop into the proper notch of the rack 20. And the rearward movement of the back carries 95 with it the forward and upward movement of the foot-rest, through the rod 25, lever 26 and link 28. The extreme positions of these parts are shown by the dotted outlines in Fig. 2. To restore the parts, as where the 100 person reclining on the swing is about to get out, he only needs to bear down on the foot-rest, which restores the foot-rest and back to their vertical positions.

As our swing is substantially all of metal, it 105 may be left out in the weather, without injury. The frame is strong and not easily injured, and yet the wire fabric affords an extremely easy, comfortable and agreeable support for the body.

What we claim is:

1. The combination of an angle-iron seat

frame, end rails and arm rests built upon said frame at the ends with means secured to the end rails for sustaining the same, an angle-iron back frame pivoted to the seat-frame, an angle-iron foot-rest frame pivoted to the seat-frame, a wire body fabric for said frames provided with spring connections with said frames, a rack under each arm-rest, a rod pivoted to the back frame at each end and terminating in a loop which engages the rack, a lever pivoted to the seat-frame at each end, a rod connecting one end of the lever with the back-frame and a link connecting the other end with the foot-rest frame.

2. The combination of an angle-iron seat-frame, angle-iron end rails supported thereon, an arm-rest on each end rail, eye-bolts for securing the arm-rest to the end-rail, chains secured to the eye-bolts for sustaining the seat, an angle-iron back-frame pivoted to the seat-frame, an angle-iron foot-rest frame pivoted to the seat-frame, a wire body fabric for each of said frames and extension springs connecting said frames with said fabrics respectively, a rack under each arm-rest and a rod at each end of the back-frame and pivoted thereto and provided with a loop for engaging said rack, a lever pivoted

to the seat-frame at each end, a rod at each end of the back-frame and pivoted thereto and connected with the upper end of the lever, and a link connecting the lower end of the lever with the foot-rest frame, substantially as described.

3. The combination of an angle-iron seat-frame, end rails and arm rests built upon said frames at the ends with means secured to the end rails for sustaining the same, an angle-iron back frame pivoted to the seat-frame, an angle-iron foot-rest frame pivoted to the seat-frame, a wire body fabric for said frames provided with spring connections with said frames, a rack under each arm-rest, a rod pivoted to the back frame at each end and engaging the rack, a lever pivoted to the seat-frame at each end, a rod connecting one end of the lever with the back-frame and a link connecting the other end with the foot-rest frame.

In testimony whereof we have hereunto set our hands in the presence of witnesses.

GEORGE P. McENTIRE.
RALPH N. McENTIRE.
